GEORGE A. PROCTOR, OF WATERTOWN, MASSACHUSETTS, ASSIGNOR TO LOVELL-McCONNELL MANUFACTURING COMPANY, A CORPORATION OF DELAWARE.

MECHANICAL HORN.

1,232,603.

Specification of Letters Patent. Patented July 10, 1917.

Application filed December 10, 1913. Serial No. 805,681.

To all whom it may concern:

Be it known that I, GEORGE A. PROCTOR, a citizen of the United States, and resident of Watertown, in the county of Middlesex and State of Massachusetts, have invented certain new and useful Improvements in Mechanical Horns, of which the following is a specification.

This invention relates to certain improvements in horns and more particularly to that type of horn in which the sound is created by vibrations of a diaphragm and which is adapted for giving warning or signaling sounds. Such horns find their greatest usefulness at the present time on motor vehicles, although they are readily adaptable for use in various other situations. My invention involves various important features relating to the means for effecting the vibration of the diaphragm upon the proper movement of a driving member. My invention in certain of its principal embodiments includes a movable toothed driving member and a lever member pivotally supported in such a manner that the movement of the teeth past the lever member imparts vibrations to the latter which vibrations cause the vibrations of the diaphragm. This pivoted lever member may be designed in various different ways but preferably it is so designed and mounted that its back and forth movements are all forced movements rather than forced movement followed by resilient return; each movement in one direction resulting in a corresponding blow on the diaphragm. The lever member may be so positioned and the frequency and length of the stroke of the lever member be such that positive forced vibrations are imparted to the diaphragm with the diaphragm and lever moving in synchronism, but by a different adjustment or a slightly different forming of the lever member the blows delivered to the latter may resemble more nearly the blows of a tapper such as is used in the ordinary "buzzer" horn, in which the movements of the armature of an electromagnet result in corresponding taps or light blows to the diaphragm, but without positive forced displacement of the diaphragm, and without synchronism with the latter.

The toothed member may be on a rotor so as to continuously travel in the same direction while the horn is being sounded and may be driven by a spring motor. I prefer-

ably employ such a spring as may be wound up and normally held in wound position and released at will for such a length of time as may be desired to sound the signal, and then relocked in its partially unwound condition. Thus it would be necessary to wind the spring only at infrequent intervals and the horn will always be in condition for sounding, by merely pressing the button. Such a construction eliminates such troubles as arise from defective wiring, short circuits, and exhausted batteries in connection with electric horns.

Reference is to be had to the accompanying drawings in which similar reference characters indicate corresponding parts throughout the several views; and in which—

Figure 1 is a side elevation of a horn constructed in accordance with my invention, a portion of the gear case being shown in section;

Fig. 2 is a view of the horn shown in Fig. 1 but in a plane at right angles to the plane of Fig. 1; and

Fig. 3 is a view somewhat similar to Fig. 1, and showing the rotor driven by a spring motor.

In the specific form shown in Figs. 1 and 2, I employ a diaphragm 10, clamped in place in any suitable manner about its periphery. To the front diaphragm clamp 11, is secured a horn or resonator 12, of any suitable shape or design. The diaphragm mounting and resonator form no portion of my present invention. The rear diaphragm clamp 13 carries a rear casing 14, in which is pivotally mounted a lever member 15 in proper operative relation to the diaphragm. One end of the lever is so mounted that during its normal swings, it will strike either the diaphragm itself at or adjacent the center or strike a suitable wear-piece on the latter. The lever member has two teeth or projections 16 and 17 on the face away from the diaphragm and adapted to engage with the teeth 18 on the periphery of a rotor 19.

The lever is so positioned in respect to the rotor and the teeth are of such size and shape that the turning of the rotor imparts positive back and forth vibrations to the lever member. In other words, when the tooth 16 is free of the rotor the tooth 17 will be between successive teeth on the rotor

and vice versa. The further movement of the rotor from the position shown in Fig. 1 will cause the lower end of the lever to swing outwardly and tap the diaphragm 5 but at the same time the upper end of the lever will swing rearwardly to bring the tooth 16 between two successive rotor teeth 18. One tooth 18 can now pass the tooth 17 and the continued rotation will force the 10 tooth 16 out and the tooth 17 will enter the space between the next two adjacent teeth 18 of the rotor and the lever will be swung in the reverse direction. As previously stated these lever swings may forcibly 15 displace the center portion of the diaphragm and the return of the diaphragm may aid in the return swing of the lever member, and the speed and design may be such as to bring the positive swings of the lever, which 20 are caused by the movement of the rotor, into synchronism with the natural body swings of the diaphragm when the latter is vibrating in its fairly definite natural time period. On the other hand blows delivered 25 by the lever 15 may be merely tapping blows which do not forcibly displace the center portion, and may thus correspond more nearly to the taps occurring in a "buzzer" horn.

30 For causing the series of teeth 18 to pass the teeth 16 and 17 and rock the lever, various mechanisms may be employed. As shown in Figs. 1 and 2 the shaft of the rotor 19 carries a pinion 20 meshing with a gear 35 wheel 21, and to the shaft of the latter is connected a crank 22. By turning the crank the rotor 19 may be driven at very high speed. The specific form illustrated in Fig. 3 corresponds in many respects with that 40 shown in Figs. 1 and 2 except that a spring and a locking mechanism are interposed between the crank and the rotor. In this figure I have shown a rotor 19^a with teeth 18^a somewhat sharper than the teeth 18 shown 45 in Fig. 1. The lever member 15^a has its teeth 18^a and 17^a correspondingly less sharp. Within the rear case 14^a is a gear wheel 23 mounted on a shaft 24 but free to rotate thereon. A heavy coil spring 25 has its 50 outer end attached to the gear wheel adjacent the periphery of the latter and its inner end attached to the shaft. The gear wheel 23 meshes with a pinion 26 which latter is rigid with a gear 27. The latter meshes 55 with a pinion 28 rigid with the rotor 19^a. The spring when wound up by turning the crank may be prevented from unwinding by any suitable form of pawl 33 and ratchet wheel 34 on the shaft 24.

60 After the spring has been wound up the rotor is normally prevented from turning by a pivoted catch 29 having a push button 30 at its outer end and a shoulder 31 at its inner end. This shoulder may normally engage directly with the teeth of one of the 65 gears, or may engage with one of a series of projecting pins 32 on the face of the gear wheel 27. This locking mechanism is normally held in operative position by a suitable spring 33 and so that the push button 30 70 extends to the exterior of the case 14^a. After the spring has been wound up it can not unwind by reason of the pawl 33 and ratchet 34, and the locking lever 29. When it is desired to sound the horn the push button 30 75 may be depressed and the rotor thus liberated to effect the diaphragm vibrations. The button may be released immediately after being depressed and the horn will continue to sound until the next pin 32 comes against 80 the shoulder 31. The distance between successive pins 32 may be selected in accordance with the desired length of time for the signal operation after the depression and release of the button. It is evident that the 85 shorter the distance between the pins and the greater the number of them, the shorter will be the signal. As far as this spring motor and releasing mechanism is concerned, I might in some constructions omit the lever 90 15^a and use the rotor as a cam wheel for direct engagement with a wear-piece on the diaphragm so as to impart partly forced and partly free body vibrations of the diaphragm as in the ordinary form of Klaxon 95 horn.

In the forms shown the intermediate lever member is mounted to either tap the diaphragm or to press against the same and 100 positively displace it.

It is of course evident that the resonators shown may be modified in shape, size and relative proportions or may be practically omitted if desired.

Having thus described my invention, what 105 I claim as new and desire to secure by Letters-Patent, is:

1. An automobile warning signal, comprising a casing having opposed substantially parallel side walls, a diaphragm closing one end of said casing and having its periphery rigidly secured to the walls of said casing, a toothed rotor rotatable about an axis parallel to said diaphragm and supported between and substantially parallel to said side walls, a rigid lever pivoted intermediate of said rotor and said diaphragm and adapted to swing in the plane of said rotor, said lever having one end thereof adapted to effect vibration of said diaphragm and having two spaced projections upon the face thereof away from said diaphragm and adapted to engage with said rotor, whereby said lever is oscillated and said diaphragm is vibrated upon the rotation of said rotor, a pinion rigid with said rotor, a gear wheel larger than said rotor meshing with said pinion, and means for rotating said gear wheel. 110 115 120 125
2. A warning signal, comprising a casing, 130

a diaphragm closing one end of said casing and having its periphery rigidly secured to the walls thereof, a toothed rotor rotatable about an axis parallel to said diaphragm and supported within said casing, a rigid lever pivoted intermediate of said rotor and said diaphragm and adapted to swing toward and from said diaphragm, said lever having one end thereof adapted to deliver 10 blows to the center of said diaphragm and having two spaced projections upon the face thereof away from said diaphragm and adapted to engage with said rotor, whereby said lever is oscillated and said diaphragm

is vibrated upon the rotation of said rotor, a 15 pinion rigid with said rotor, means meshing with said pinion and normally tending to rotate it, and means manually operable from the exterior of said casing for preventing or permitting said rotation.

Signed at Waltham in the county of Middlesex and State of Massachusetts this 6th day of December A. D. 1913.

GEORGE A. PROCTOR.
